The ornamental design for a bodily fluid drainage bag cover, as shown and described.

DESCRIPTION

FIG. 1 is a perspective view of a bodily fluid drainage bag cover;

FIG. 2 is a front elevation view thereof;

FIG. 3 is a right side elevation view thereof, it being understood that a left side elevation view thereof is a mirror image of FIG. 3;

FIG. 4 is a top plan view thereof;

FIG. 5 is a bottom plan view thereof;

FIG. 6 is another perspective view thereof in which the bodily fluid drainage bag cover is attached to a bodily fluid drainage assembly and is in a lowered state; and,

FIG. 7 is another perspective view thereof in which the bodily fluid drainage bag cover is attached to a bodily fluid drainage assembly and is in a partially raised state.

The broken lines immediately adjacent the shaded areas represent the bounds of the claimed design, while all other broken lines are directed to environment and are for illustrative purposes only; the broken lines form no part of the claimed design.
